DESIGN FOR A NAVIGATION INSTRUMENT FOR AIRCRAFT

Jack C. Wilson, Garden City, N. Y., assignor to
Sperry Gyroscope Company, Inc., a corporation
of New York

Application June 29, 1946, Serial No. 131,211

Term of patent 7 years

(Cl. D52—1)

To all whom it may concern:

Be it known that I, Jack C. Wilson, a citizen
of the United States, residing at Garden City, in
the county of Nassau and State of New York,
have invented a new, original, and ornamental
Design for a Navigation Instrument for Aircraft,
of which the following is a specification, refer-
ence being had to the accompanying drawing,
forming a part thereof.

Figs. 1 and 2 are views in perspective, respec-
tively, of the front and rear of a navigation in-
strument for aircraft, showing my design.

I claim:

The ornamental design for a navigation instru-
ment for aircraft, as shown.

JACK C. WILSON.
